UNITED STATES PATENT OFFICE.

GUSTAV KNICKELBEIN, OF MILWAUKEE, WISCONSIN.

SCENE-SHIFTING APPARATUS.

1,241,637.

Specification of Letters Patent.

Patented Oct. 2, 1917.

Application filed June 7, 1916. Serial No. 102,119.

To all whom it may concern:

Be it known that I, GUSTAV KNICKELBEIN, a citizen of the United States, and resident of Milwaukee, in the county of Milwaukee, 5 and State of Wisconsin, have invented new and useful Improvements in Scene-Shifting Apparatus, of which the following is a description, reference being had to the accompanying drawings, which are a part of this 10 specification.

The invention relates to theatrical apparatus.

The invention is more particularly designed to provide an apparatus or device for 15 operating scenery.

Heretofore it has been customary in theaters to suspend each set of scenery from three or more ropes running over pulleys in the loft of the theater and to provide these 20 ropes with what is termed an equalizer and secure a counter weight, generally a sand bag, to the equalizer. In the manipulation of scenery of this kind the ropes above referred to are tied down to the pin rail in 25 the fly gallery when the scene is up or down. The counter weight is generally secured to the equalizer directly above the head of the attendant who stands at the pin rail in the fly gallery so that he may 30 see what is going on on the stage below him and it sometimes happens that these counter weights fall upon or strike the attendants causing injury. Thus it has been the practice to provide a counter weight for each 35 piece of scenery and to so position the counter weight upon the scene supporting ropes as to be dangerous to the attendants in the fly gallery. Furthermore the use of a counter weight for each scene near the pin rail 40 means more space required in the fly gallery. In view of the disadvantages above pointed out, I have provided a device whereby a single counterweight may be used in connection 45 with several sets of scenes and operated from the fly gallery, and one in which the counter weight is connected to the scene shifting ropes in such a way as to be back of the pin rail and behind the operator.

The invention further consists in the several features hereinafter set forth and is more particularly defined by claims at the conclusion hereof.

In the drawings:

Figure 1 is a view of the theatrical stage 55 looking from the rear toward the front thereof with the device embodying the in-

vention applied to one of the pieces of scenery:

Fig. 2 is an enlarged detail view of a portion of the device embodying the invention.

Referring to the drawing the numeral 3 represents the stage, 4 the proscenium of the stage, 5 a drop scene, 6 the stage loft, and 7 the fly gallery from which the scenes are 65 operated.

In the present instance the drop scene or curtain 5 is connected to three ropes 8, 9 and 10 running over pulleys 8', 9' and 10' journaled in suitable supports 11 mounted 70 on the frame member 12 of the loft 6. From the pulleys 8', 9' and 10' the ropes pass over pulleys 8'', 9'' and 10'' journaled in a bracket 13 mounted on the frame 12 and from thence said ropes extend downwardly to the pin rails 14 and 15 beneath the loft 6 and at the front of the fly gallery 7. The scene 5 is adapted to be tied off in either lowered or raised position by securing the ropes 8, 9 and 10 to one of the belaying 80 pins 16 on either of the pin rails 14 and 15.

The equalizer for equalizing the pull on the ropes 8, 9 and 10 in the present instance consists of a single pulley 17, the shell of which is directly connected to the middle 85 rope 9 by a rope 18 and a rope 19 connected at its end to the ropes 8 and 10 respectively passes through the sheave of said pulley. The pulley 17 is provided with an eye bolt or other suitable fastener 20. While I have 90 shown and described a single scene and the connections for raising and lowering it, it will be understood that the invention is used in the theater in connection with several 95 scenes arranged one behind the other and that each scene is suspended from the loft in the manner just described and that the operating ropes run down to the pin rail in the fly gallery.

The counter weight mechanism which is 100 designed to be used in connection with several single scenes hung as above described comprises a counter weight 21 which is connected to a rope 22 passing upwardly and thence horizontally over spaced apart pulleys 23 and 24 mounted in the loft above the fly gallery and thence downwardly and around a pulley 25 mounted on the floor of the fly gallery behind the pin rail and in line with the ropes 8, 9 and 10 connected 110 to the scene 5, and it further comprises means for detachably connecting said coun-

ter weight mechanism to the ropes 8, 9 and 10. This means consists of a pulley 26 through which the end portion 27 of the rope 22 passes, the end of the rope 22 being provided with a snap hook 28 which is adapted to be detachably secured in a ring 29 tied or otherwise fastened to the rope between the pulleys 25 and 26 and on the side opposite to the end portion 27. The 10 pulley 26 is provided with a hook 30 which is adapted to be hooked into the fastener 20 on the pulley 17 of any one of several scenes.

As shown in full lines in Fig. 1 the counter weight mechanism is connected up to the 15 ropes supporting the scene 5 and in this condition counter balances or tends to counter balance the weight of said scene when it is raised or lowered. If now it is desired to raise or lower a scene in front of, behind or 20 within a reasonable distance from the scene 5, scene 5 is tied off in raised position by tying the ropes 8, 9 and 10 to one of the belaying pins on one of the pin rails in the front of the fly gallery. When this is done the operator unhooks the snap hook 28 from engagement with the ring 29 and the rope 22 is then pulled by the counter weight 21 until the tied ring 29 engages the pulley 25, as shown in dotted lines in Fig. 1. This brings 25 the counter weight 21 to rest and gives sufficient slack in the end portion 27 of the rope 22 to enable the operator to unhook the pulley 26 from the pulley 17 for the scene 5 after which he may hook up the pulley 26 30 with the pulley 17 of any one of several scenes near the scene 5 and then secure the snap hook 28 to the ring 29 to connect the counter weight mechanism with this other scene. Thus the single counter weight mechanism 35 serves for several scenes.

It is to be noted also that the arrangement of the blocks and connections for the counter weight are such as to dispose the counter weight at the rear of the fly gallery and 40 behind the operators, so that there will be no chance of their being injured while stationed at the pin rail to manipulate the scenes.

The invention thus exemplifies a simple and efficient form of scene shifting apparatus which is well adapted for the purpose described.

The invention is not to be understood as restricted to the details set forth, since these may be modified within the scope of the appended claims without departing from the spirit and scope of the invention.

What I claim as my invention is:

1. The combination, with a plurality of scenes, a plurality of ropes for suspending each of said scenes, and a pin rail in the fly gallery for tying off the ropes for each scene, of a counter weight mechanism comprising a rope and a weight suspended by said rope from the stage loft, a detachable 60 connection between said rope and the ropes 65

for any one of said scenes, and means for lengthening and shortening said counter weight rope to facilitate the change of the counter weight mechanism from one scene to another.

2. The combination, with a plurality of scenes, a plurality of ropes for suspending each of said scenes, and a pin rail in the fly gallery for tying off the ropes for each scene, of an equalizer secured to the ropes 70 for each scene, pulleys in the stage loft and a pulley on the floor of the fly gallery, a rope running over pulleys in the stage loft and the pulley on the floor of the fly gallery, a counter weight secured to the end of the 75 rope at a distance from the pin rail, an extensible connection on the end of the rope near the pulley on the floor of the fly gallery, a member slidably mounted on said extensible portion of the counter weight rope, 80 and a detachable connection between said member and said equalizer.

3. The combination, with a plurality of scenes, a plurality of ropes for suspending 90 each of said scenes, and means for tying off each of said scenes, of a counter weight mechanism comprising a rope and a weight connected thereto, a detachable connection between said rope and the ropes for any one 95 of said scenes, and means for lengthening or shortening said counter-weight rope while the change of the counter weight mechanism from one scene to another is being made.

4. The combination, with a plurality of scenes, a plurality of ropes for suspending 100 each of said scenes, and means for tying off each of said scenes, of an equalizer secured to the ropes for each scene, a counter weight mechanism adapted to be detachably connected to any one of said equalizers comprising 105 a rope and a counter weight connected thereto, one end of said rope having a loop therein formed by detachably connecting this end of the rope to an intermediate portion thereof, a member slidably mounted on the loop, and a detachable connection 110 between said member and said equalizer.

5. The combination, with a plurality of scenes, a plurality of ropes for suspending 115 each of said scenes, and means for tying off each of said scenes, of a counter weight mechanism comprising a rope and weight connected thereto, a detachable connection between said rope and the ropes for any one 120 of said scenes, means for limiting the travel of the counter weight and rope, and means for lengthening or shortening said counter weight rope while the change of the counter weight mechanism from one scene to another 125 is being made.

6. The combination, with a plurality of scenes, a plurality of ropes for suspending each of said scenes, and a pin rail in the fly gallery for tying off the ropes for each 130

scene, of a counter weight mechanism including a rope and a weight suspended by said rope from the stage loft to a position in the fly gallery at a distance from the pin rail, and an extensible detachable connection between said counter weight rope and the ropes for each scene to permit said counter weight mechanism to be used in connection with a plurality of scenes.

5 7. The combination, with a plurality of scenes, a plurality of ropes for suspending

each of said scenes and a pin rail in the fly gallery for tying off the ropes for each scene, of a counter weight mechanism having a part extending to a position adjacent the pin rail, and an extensible detachable connection between said counter weight mechanism and the ropes for each scene to permit said counter weight mechanism to be used in connection with a plurality of scenes.
